J. B. COX, JAMES O'CONNOR, AND MICHAEL CAHALAN, OF COLUMBUS,
GEORGIA.

Letters Patent No. 97,886, dated December 14, 1869.

IMPROVED RAILWAY-SWITCH.

The Schedule referred to in these Letters Patent and making part of the same.

To all whom it may concern:

Be it known that we, J. B. COX, JAMES O'CONNOR, and MICHAEL CAHALAN, of Columbus, in the county of Muscogee, in the State of Georgia, have invented a new and useful Improvement in Railroad-Switches; and we do hereby declare that the following is a full and exact description thereof, reference being had to the accompanying drawings, and the letters of reference marked thereon.

Our invention consists in the arrangement of two sets of switch-rails, that are operated upon by cranks upon a rock-shaft, and with which they are connected by jointed links, one set of such switch-rails being moved a greater distance than the other, so that with such arrangement, the switch-rails, when moved from the straight track, will connect with each other, and with the standing sideling track, and be in a curved line, instead of, as is generally the case, in straight lines, and forming angles at their point of meeting, with the special operating-devices.

Figure 1 is a plan view of the arrangement of the tracks, when laid upon our improved method, and the mode of operating the same.

Figure 2 is a transverse section of the same.

To enable others skilled in the art to construct and use our invention, we will describe its construction and operation.

The bed of the track is provided with the proper ties and sills, to support firmly, and in the proper place, the rails and their chairs.

A A represent the long switch-rails, having one end at *a*, inserted in the chair, to meet the fixed rail in the permanent track.

Near to the other end of rails A A is the coupling-bar D, which is fastened to the rails, and connects with link H, which is attached to crank E' of the rock-shaft E, which is suitably secured, and so that it will freely rotate on its axis; as the switch-rails are sprung in either direction, one will strike against stop-chairs b, which will cause the rails to be in curve line, when in their position, to connect with the sideling track or rails B' and C', which are also curved, to correspond with the curvature of the switch-rails A A, when turned to meet them.

Situated between switch-rails A A and the inner rails of the standing sideling tracks B' B' C' C', and standing straight tracks A' A', are the short switch-rails B B and B' B'.

The ends of these rails B and B', at *x*, are fixed in chairs, and in the position shown. The other ends are so that they can be moved to be coincident with the standing curved rails B' B' C' C', and standing straight rails A' A', by means of coupling-bar D', link H', and crank E", upon rock-shaft E.

Upon the cross-sills are stop-chairs e, which, as the

ends of the rails B and B' are moved to one side or the other, will cause them to curve, to correspond with the curvature of the switch-rails A A, B' B', and C' C'.

At the centre of the length of the rock-shaft E, is the operating-lever F, and so arranged, with relation to the rock-shaft and its cranks E' E", that when it is perpendicular above the shaft, the cranks will be perpendicular under the shaft E.

Crank E' is of the length to move the rails A A from their position of connecting with the straight track, to connect with short switch-rails, as shown in dotted lines in fig. 1, and crank E" is of the length from the shaft to move the rails B, to connect with the rails B' and rails B', to connect with rails C'.

Crank E' is usually one-half the length of crank E", so that the rails A A will move twice as far by turning the lever F, as the rails B and B' will move, but must, in all cases, be so proportioned that the moving of the lever F from its perpendicular position over to a horizontal, that the switch-rails will always be coincident or connect with the standing rails.

Lever F is made to pass between the legs of the stand, which are so formed as to be of sufficient strength to hold the lever in its perpendicular position, where it can be held by pin *a*, that goes through the holes in the stand, and a corresponding hole in the lever.

When the lever is thrown over to a horizontal position, the switch-rails are moved to either one side or the other of the straight track, on to sideling tracks, and is held in such horizontal position by means of a mortise in the lever, going over a staple in the platform or sill, and passing the holding-pin *a*, through the staple above the lever.

By this arrangement of the switch-rails with the standing track and sideling, the use of the frogs, that generally intervene, are done away with, thus saving much expense in construction, and having a switch that is always safe and reliable, easy of operation, and durable.

Having thus described our invention,

What we claim, and desire to secure by Letters Patent, is—

The combination of the switch-bars A A, B B, and B' B', stop-chairs b and e, with the coupling-bars D and D', links H H', cranks E' E", rock-shaft E, and lever F, all constructed and arranged to operate in the manner and for the purpose substantially as described.

J. B. COX.

JAMES O'CONNOR.

MICHAEL CAHALAN.
